[57] CLAIM

The ornamental design for a leash handle, as shown and
described.

DESCRIPTION

FIG. 1 is a perspective view of a leash handle showing
my new design;

FIG. 2 is a front elevational view thereof;

FIG. 3 is a rear elevational view thereof; and

FIG. 4 is an elevational view of one end thereof, the
opposite end being the same as the end shown.

The broken-line showing of a leash in FIG. 1 is for
purposes of illustration only and forms no part of the
claimed design.
